US00D558602S

(12) **United States Design Patent** (10) **Patent No.:** **US D558,602 S**
Kissner et al. (45) **Date of Patent:** **** Jan. 1, 2008**

(54) **SLEEVE FOR CONTAINERS**

(75) Inventors: **Douglas R. Kissner**, Glenview, IL (US); **Surendra H. Agarwal**, Glenview, IL (US); **Joseph M. Miskovic**, Plainfield, IL (US); **Travis A. Larson**, Antioch, IL (US)

(73) Assignee: **Kraft Foods Holdings, Inc.**, Northfield, IL (US)

(**) Term: **14 Years**

(21) Appl. No.: **29/240,253**

(22) Filed: **Oct. 11, 2005**

(51) **LOC (8) Cl.** **09-05**

(52) **U.S. Cl.** **D9/711**

(58) **Field of Classification Search** D9/711, D9/702, 713, 719, 738-740, 517-518, 522, D9/416, 460-435, 444, 438, 455, 499, 414, D9/739; D7/560-562; 206/434, 427, 426, 206/429, 430, 485, 485.1, 499, 508; 229/117.13, 229/185, 121-122, 200, 207, 236, 237; 220/23.83

See application file for complete search history.

(57) **CLAIM**

The ornamental design for a sleeve for containers, as shown and described.

DESCRIPTION

FIG. 1 is perspective view of a sleeve for containers showing our new design;

FIG. 2 is a top plan view thereof;

FIG. 3 is a left side elevational view thereof;

FIG. 4 is a bottom plan view thereof;

FIG. 5 is a front elevational view thereof; the rear elevational view being the mirror image thereof; and,

FIG. 6 is the right side elevational view thereof.

The top opening feature in FIGS. 1 and 2 are shown in broken lines for illustrative purposes only and form no part of the claimed design.

1 Claim, 4 Drawing Sheets
